UNITED STATES PATENT OFFICE.

LAWRENCE RICHARDSON, OF CHICAGO, ILLINOIS.

YOKE CONSTRUCTION.

Application filed August 28, 1924. Serial No. 734,590.

To all whom it may concern:

Be it known that I, LAWRENCE RICHARDSON, a citizen of the United States, residing at Chicago, in the county of Cook and State 5 of Illinois, have invented certain new and useful Improvements in Yoke Constructions, of which the following is a specification.

This invention relates to a railway car 10 draft yoke.

In the ordinary integrally formed draft yoke the weakest points at the rear end thereof are at the inner points of joining between the draft arms and the rear connecting member. When a car is subjected to a jerk, the draft arms are subjected to tension which is fairly uniformly distributed in said arms, but the jerk is finally resisted by the draft gear or other appliance, which 20 causes the load to be delivered at the critical points in question. A beam action results with the deflection taking place in the center of the rear connecting member. This deflection increases the tension stress at the 25 two high tension points.

One object of the invention is to minimize the excessive tension stresses at the critical points in question in a simple and efficient manner.

Another object is to provide a simple, durable and reliable draft yoke construction in which the tension stresses at the inner points of joining between the draft arms and rear connecting member are appreciably reduced or neutralized.

These and other objects are accomplished by means of the yoke construction disclosed on the accompanying sheet of drawings, in which—

Figure 1 is a side elevation of a railway car draft yoke embodying my invention;

Figure 2 is a top plan view thereof; and

Figure 3 is a side elevation of the general type of draft yoke in common use.

Referring first to Figure 3, it will be noted that the usual integral type of draft yoke includes upper and lower arms 10 and 11, respectively, which are connected to each other by a rear connecting member 12. In 45 this particular instance the front ends of the arms are connected by a strap 13, one

at each side. It will be noted that the arms 10 and 11 in Figure 3 are straight throughout their lengths rearwardly from a point not far distant from the front ends thereof. As mentioned hereinabove, when a car is subjected to a jerk, excessively high tension stresses are concentrated at the inner connecting points of the arms 10 and 11 and the rear connecting member 12, the stress 55 being increased as the result of a beam action in the cross member 12 due to engagement with the usual draft gear member 15.

To overcome the excessive tension at the points in question, in the manufacture of 60 yokes, the draft arms 16 and 17, respectively, as shown in Figure 1, are bowed outwardly adjacent the rear connecting member 18, or more particularly are bowed outwardly at a point forwardly from the critical 65 tension points 19 and rearwardly of the vertical transverse middle of the yoke. With this arrangement, when a car is subjected to a jerky draft force, the bowed portions 20 of the draft arms 16 and 17 will have a 70 tendency to straighten, causing, in so far as this straightening action is concerned, a concentration of compressive force or action at the critical points 19, thereby reducing the total amount of tension at such points. 75 In this way the excessively high tension stresses at the critical points 19 are greatly reduced, thereby relatively increasing the strength of the yoke.

I claim:

1. A railway draft yoke comprising draft arms and a rear connecting member all formed in a single integral piece wherein under jerky draft conditions relatively high tension stresses tend to concentrate at the 90 inner points of joining between said draft arms and rear member, said arms adjacent said rear member and forwardly of said points of joining being bowed outwardly to reduce the tension stresses at said points. 95

2. A railway car draft yoke comprising draft arms and a rear connecting member all formed in a single integral piece wherein under jerky draft conditions relatively high tension stresses tend to concentrate at the 100 inner points of joining between said draft arms and rear member, said arms inter-

mediate their ends being bowed to reduce the tension stresses at said points.

3. A railway car draft yoke comprising draft arms and a rear connection member 5 all formed in a single integral piece wherein under jerky draft conditions relatively high tension stresses tend to concentrate at the inner points of joining between said draft

arms and rear member, said arms forwardly of said high tension points being bowed 10 outward to reduce tension stresses at said points.

Signed at Chicago, Illinois, this 22nd day of August, 1924.

LAWRENCE RICHARDSON.
